United States Patent [19]

Sakamoto

[11] Patent Number: Des. 283,817

[45] Date of Patent: ** May 13, 1986

[54] CENTRAL PROCESSING UNIT FOR COMPUTER

[75] Inventor: Junichi Sakamoto, Osaka, Japan

[73] Assignee: Sharp Corporation, Osaka, Japan

[**] Term: 14 Years

[21] Appl. No.: 544,355

[22] Filed: Oct. 21, 1983

[30] Foreign Application Priority Data

Apr. 21, 1983 [JP] Japan 58-17130

CLAIM

The ornamental design for a central processing unit for computer, as shown and described.

DESCRIPTION

FIG. 1 is a perspective view of the central processing unit for computer showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and

FIG. 7 is a bottom plan view thereof.
